UNITED STATES PATENT OFFICE.

VICTOR R. WILL, OF SACRAMENTO, CALIFORNIA.

DESIGN FOR AN ORNAMENTAL LAMP.

Application filed October 17, 1923. Serial No. 7,529. Term of patent 3½ years.

To all whom it may concern:

Be it known that I, VICTOR R. WILL, a citizen of the United States, residing at Sacramento, in the county of Sacramento and State of California, have invented a new, original, and ornamental Design for an Ornamental Lamp, of which the following is a specification, reference being had to the accompanying drawing, forming a part thereof, in which—

Fig. 1 is a front view of an ornamental lamp, and

Fig. 2 is a side or end view of the same, showing my new design.

I claim:—

The ornamental design for an ornamental lamp as shown.

VICTOR R. WILL.
